UNITED STATES PATENT OFFICE.

JOHN P. FERRITER, OF OCEANPORT, AND WRIGHT H. JOHNSON, OF RED BANK,
NEW JERSEY.DEVICE FOR REPEATING ALTERNATING-CURRENT TELEGRAPH SIGNALS BY MEANS
OF VACUUM TUBES.

Application filed August 29, 1923. Serial No. 660,023.

To all whom it may concern:

Be it known that we, JOHN P. FERRITER and WRIGHT H. JOHNSON, citizens of the United States, residing, respectively, at 5 Oceanport and Red Bank, in the county of Monmouth and State of New Jersey, have invented certain new and useful Improvements in Devices for Repeating Alternating-Current Telegraph Signals by Means of 10 Vacuum Tubes, of which the following is a specification.

This invention relates to vacuum tube repeaters and more especially such as are employed in line telegraph circuits.

15 The present types of telegraph repeaters in use are not satisfactory due to mechanical reasons and to repeater lag which causes attenuation of signals. If several sets of repeaters are used, false signals result. Up 20 to the present time vacuum tube repeaters have been impracticable due to the fact that direct current has largely been used for line current. By using alternating line current, the use of tube repeaters is possible and 25 profitable. False signals and other repeater troubles are thereby eliminated.

In order to more clearly disclose the nature of our invention the following figures of the drawing are attached and in which:

30 Figure 1 represents an arrangement for two-tube two-way repeaters.

Figure 2 represents a two-way four-tube repeater system.

Referring more particularly to the drawings, Figure 1 shows an iron core transformer M having the primary windings O^1 and O^2 and the secondary windings, P , and P^2 . A similar transformer m is also provided. N and n are iron core transformers 40 provided with suitable windings. Tubes 1 and 2 are three-electrode vacuum tubes lighted by a battery A . The plate potential for the tubes is furnished by batteries B and b . The grids of the tubes are properly biased 45 for correct operation by means of batteries C and c . AL and al are artificial line rheostats and condensers for the purpose of balancing the repeaters.

The artificial line rheostats and condensers 50 AL are adjusted until a current introduced into the middle point of windings O^1 and O^2 of the transformer M by means of the trans-

former N divides equally through O^1 to line and O^2 to artificial line. This is similar to balancing an ordinary duplex. A similar 55 balance must be obtained for al so that current supplied by the transformer n divides equally through p^1 and p^2 to the artificial line. Thus P , and P^2 are balanced against outgoing current furnished by transformer 60 N and a similar condition obtains for p^1 and p^2 , and n .

Suppose that an alternating current, the half-waves of which have their amplitudes modified according to any predetermined 65 signalling flow, comes in over the line alternating current through O^1 and through O^2 and AL in parallel with the secondary of N to the ground. There is then an unbalance of current in O_1 and O_2 . An alternating electro-motive force will then be induced across the windings P_1 and P_2 in series and impressed on the grid of the tube 1. A large alternating vibration takes place in the plate circuit of tube 1, which by means of the 70 transformer n , impresses a voltage upon the middle point of p^1 and p^2 . Since the current through these coils is equal and in opposite directions, no voltage will be induced in windings O_1 and O_2 and therefore no variation of grid voltage will take place. The 75 action of the repeater upon a signal entering p^2 is similar to that described above.

Figure 2 shows a repeater using four tubes. The object of this system is to divide 80 the voltage across windings P_1 and P_2 (p^1 and p^2) between two grids so that approximately one-half the voltage is placed upon the grid as is the case when single tubes are used. This allows the tubes to be worked to 85 better advantage and prevents distortion. The system of balancing is the same as described above.

Suppose that a signal impressed on M at 90 a given instant makes the grid of tube 1 positive and the grid of tube 2 negative. The plate current of tube 1 will increase through S^1 , and the plate current of tube 2 will decrease through S^2 . A voltage will be induced in p^1 and p^2 in series. At the next 95 half cycle the grid of tube 1 becomes negative and the grid of tube 2 becomes positive so that the plate current of tube 1 decreases through S^1 and the plate current 100

of tube 2 increases through S^2 . The action of tubes 3 and 4 is similar to that above described.

Having thus described our invention, we claim:

In combination with a vacuum tube duplex amplifier, an alternating current telegraph line, a plurality of pairs of three-electrode vacuum tube detectors, each tube of 10 said pairs having its filament in series with that of another, each pair having an iron core transformer of primary and secondary windings, said primary being connected to said line and to the grid of one tube, said 15 secondary being connected to an artificial line and to the grid of the other tube, another transformer having its primary and

secondary windings connected to the plates of said tubes, the primary of said transformer being also connected to another set 20 and to a transformer corresponding to the first mentioned transformer, the latter being also connected to said second set and to the primary of a transformer corresponding to said second mentioned transformer, for the 25 purpose of providing means for impressing a substantially sustained signalling alternating current the half-waves of which have their amplitudes modified according to any predetermined signalling flow. 30

In testimony whereof we affix our signatures.

JOHN P. FERRITER.
WRIGHT H. JOHNSON.
